CONTROL KNOB FOR OFFICE MACHINES

Ellen V. B. Ludwick, Syracuse, N.Y., assignor to
SCM Corporation

Filed Dec. 8, 1972, Ser. No. 313,204

Term of patent 14 years

Int. Cl. D8—06

U.S. Cl. D8—145

FIG. 1 is a front perspective view of a control knob for office machines showing my new design.

FIG. 2 is a rear perspective view of FIG. 1.

I claim:

The ornamental design for a control knob for office machines, substantially as shown.
